GOODRICH Q. LEWIS, OF WHEATON, ILLINOIS, ASSIGNOR TO WILLIAM H. MINER, OF CHAZY, NEW YORK.

DRAFT-RIGGING FOR CARS.

1,228,572.

Specification of Letters Patent.

Patented June 5, 1917.

Application filed October 18, 1915. Serial No. 56,437.

To all whom it may concern:

Be it known that I, GOODRICH Q. LEWIS, a citizen of the United States, residing at Wheaton, in the county of Dupage and 5 State of Illinois, have invented a certain new and useful Improvement in Draft-Rigging for Cars, of which the following is a full, clear, concise, and exact description, reference being had to the accompanying 10 drawings, forming a part of this specification.

This invention relates to improvements in draft riggings for cars.

The object of the invention is to provide 15 relatively cheap draft attachments for a railway car draft rigging, the attachments being so designed that they may be easily applied and preferably made from commercial shapes.

20 In the drawing forming a part of this specification, Figure 1 is a longitudinal, vertical sectional view of a draft rigging showing my improvements embodied therein, and Fig. 2 is a horizontal, sectional view of the 25 structure shown in Fig. 1 and taken substantially on the line 2—2 of the latter.

In said drawing, 10—10 denote the center sills or draft members of the car, the same being preferably in the form of channels 30 having their flanges extended outwardly, 11—11 denote the rear stop members and 12—12 the front stop members. Each of the stop members 11—12 is in the form of a section of a channel, with the channel extending lengthwise or parallel to the center line of the draft rigging. Each of the stop members 11 has the flange portions 13—13 thereof riveted to the draft members 10, the upper stop member 11 having its flanges extending upwardly and the lower stop member 11 having its flanges extending downwardly. Each of the rear stops 11 also has a portion of the web 14 thereof cut away at the front end to thereby form a recess or pocket within which fits the rear end 40 of the draft gear, designated generally by the reference A. In order to brace the stop members 11 and to form wider bearings for the stop shoulders proper, each of the stop members 11 has another section of a channel 15 secured thereto preferably by rivets. The channel sections 15 extending transversely of the stop members are at right angles to the channels forming the stop members 11. Each of the channel sections 15 is

so positioned that the forward flange 16 thereof is flush with the front edge of the web 14 thus forming a wide and rigid abutment for the rear end of the casing of the draft gear A. By arranging the rear stops 11—11 in the manner described, I provide long flange sections by which the same may be riveted to the sills, thus distributing the rivets over a large area. Each of the stop members 12—12 has also secured thereto a transversely extending section of a channel 17, the inner or rear flanges 18 thereof being flush with the rear edges of the webs of the channel stop members 12—12. The sets of front and rear stop members 12 and 11 are spaced vertically sufficiently to receive therebetween, and also guide, a horizontal web 19, the same surrounding the draft gear A and keyed by a coupler key 20 to the draw-bar 21, the ends of the key 20 being slidable in elongated slots 22 in the sills 10. A front follower 23 is preferably interposed between the rear end of the draw-bar and the wedge of the friction mechanism of the gear A. Transversely extending tie plates 24 and 25 may be employed to support the gear and front follower respectively.

From the preceding description, it will be seen that I have provided a cheap but strong form of stop members or attachments for a draft rigging, and the same may be made entirely from commercial shapes of any requisite strength. Also, the transversely extending channel sections 15 and 17 present a large area by which they may be riveted to the stop members 11—12, thus minimizing any tendency of the webs of the stop members to bend or buckle under shock.

Various changes and modifications will suggest themselves to those skilled in the art, and I do not wish to be limited to the exact structure shown and described but contemplate all changes and modifications within the scope of the appended claims.

I claim:

1. In a draft rigging, the combination with draft sills and channel shaped stop members secured thereto, said channel stop members extending parallel to the axis of the draft rigging, of means for bracing said stop members, said means comprising channels extending at right angles to the axis of the draft rigging.

2. In a draft rigging, a stop member comprising a section of a channel arranged to

100

105

110

have the flanges thereof secured to a pair of draft sills, and a section of another channel secured to the web of said first named channel section and having one of the flanges thereof flush with the edge of the web of said first named channel section.

3. A stop member for draft riggings which comprises a section of a channel adapted to have the flanges thereof secured 10 to opposite draft sills, a portion of the web of said channel being cut out to thereby form a recess, and a section of another channel secured to the web of the first named channel and extending in a direction transversely thereof, one of the flanges of the 15 second named channel section being flush with the edge of the web of the first named

channel section at the inner end of said recess.

4. In a draft rigging, the combination 20 with draft sills, of upper and lower stop members for a draft gear having a horizontal yoke, said stop members being each secured at its sides to the sills and having a horizontal web, the upper stop member being provided at its inner edge with a transverse, vertical, upwardly extending flange and the lower stop member being provided at its inner edge with a transverse, downwardly extending, vertical flange. 25

In witness that I claim the foregoing I have hereunto subscribed my name this 27th day of Sept., 1915.

GOODRICH Q. LEWIS.
